UNITED STATES PATENT OFFICE.

EMMIT G. LATTA, OF FRIENDSHIP, NEW YORK, ASSIGNOR TO THE POPE MANUFACTURING COMPANY, OF PORTLAND, MAINE.

VELOCIPED.

SPECIFICATION forming part of Letters Patent No. 396,164, dated January 15, 1889.

Application filed January 20, 1888. Serial No. 261,361. (No model.)

To all whom it may concern:

Be it known that I, EMMIT G. LATTA, of Friendship, in the county of Allegany and State of New York, have invented new and useful Improvements in Velocipedes, of which the following is a specification.

The objects of this invention are to construct a light and rigid wheel, and to provide a simple and efficient journal-bearing which 10 can be readily adjusted for wear; also to improve the construction of the forks, so that the journal-bearings can be attached to the same in an inexpensive manner without the employment of brazed joints, and so that all 15 the parts may be detached, if necessary, for making repairs.

The invention consists to these ends of the improvements which will be hereinafter fully set forth, and pointed out in the claims.

20 In the accompanying drawings, consisting of two sheets, Figure 1 is a side elevation of the central part of my improved velocipede-wheel and connecting parts. Fig. 2 is a sectional elevation of one of the journal-bearings and connecting parts. Fig. 3 is a vertical cross-section of the adjustable collars forming part of the journal-bearing, the collars being detached from each other. Fig. 4 is an interior face view of one of said adjusting-collars. Fig. 5 is an elevation of one end of the axle and connecting parts. Fig. 6 is a vertical cross-section in line xx , Fig. 2. Fig. 7 is a horizontal section in line yy , Fig. 2. Fig. 8 is a vertical cross-section in line zz , Fig. 2. Fig. 9 is a sectional elevation of the central part of the rear wheel of a velocipede provided with my improvements.

Like letters of reference refer to like parts in the several figures.

40 A represents the axle of the front wheel, which is provided near opposite ends with a pyramidal or tapering flat-sided shank, a , and B are the hub-flanges, which are each provided with an opening, b , of corresponding form which fits over the shank a . The axle A is formed with a contracted cylindrical extension, a' , which is provided at its outer end with a screw-thread.

B' is a tubular extension formed on the 50 outer side of the hub-flange and surrounding the cylindrical extension a' of the axle.

C represents the crank applied to the end of the tubular extension B', and secured thereto by a screw-nut, c , applied to the screw-threaded outer end of the cylindrical extension a' .

D is a collar surrounding the tubular extension B' and interposed between the outer side of the hub-flange B and the boss of the crank C. The screw-nut c forces the crank 60 C against the collar D, and secures the latter firmly on the tubular extension B', and at the same time wedges the angular opening of the hub-flange upon the pyramidal shank a and rigidly secures the hub-flange to the axle. 65 The crank is held against turning upon the tubular extension B' by a key which has a limited play in its seat in the tubular extension B', as represented in Fig. 2. The screw-nut c is provided in its outer face with two 70 openings or recesses for receiving a suitable pronged wrench for turning the nut.

E is the journal-box or outer case of the ball-bearing, provided on its upper side with a lug, E', whereby it is secured to the lower 75 end of the fork-arm F.

G G' represent two adjustable collars arranged within the case E, and provided in their adjacent faces with annular grooves. The collar D, surrounding the tubular extension B', forms the inner portion of the bearing, and is provided in its outer surface with an annular groove, d , which, together with the grooves of the collars G G', forms the cavity for the balls h . The collars G G' are respectively provided on their outer surfaces with right and left hand screw-threads g g' , which engage with corresponding threads formed in the bore of the case E.

g^2 represents segmental ribs or projections 90 formed on the adjacent inner edges of the collars G G', and having beveled inner faces, the ribs of one collar projecting into the spaces between the ribs of the other collar when the collars are in an operative position, so that 95 upon turning either collar its ribs will bear against the ribs of the other collar, thereby causing both collars to move toward or from each other simultaneously. The portions g^3 of the inner edges of the collars arranged between the segmental ribs g^2 are beveled to correspond to the bevel of said ribs, as shown

in Figs. 2, 3, and 5, so that when the two collars are screwed against each other the ribs g^2 of one collar will overlap the beveled edge g^3 of the other collar. The inner smooth portions of the collars are slightly reduced in diameter, so as to permit the inner edges of the collars to pass beyond the center of the bore of the case E without injuring the screw-threads of the latter. After the collars G G' have been independently screwed into the case E sufficiently to cause their ribs g^2 to interlock, both collars can be adjusted toward each other simultaneously for taking up wear. The outer collar, G, is provided with a projection, g^4 , for turning the same, which projection consists, preferably, of a screw seated in the outer face of the collar and having its head projecting beyond the latter.

The bearing box or case E is divided in the usual manner, and provided at its adjacent ends with perforated ears or lugs, through which passes a clamping-bolt, as represented in Figs. 1 and 6.

In the constructions heretofore employed one collar was held against turning by a set-screw or otherwise, and the adjustment was effected by screwing up the other collar. This arrangement is objectionable, however, because the upper parts of the collars, which receive the greatest wear, are not kept together or opposite each other when adjusted, which is desirable in order to avoid the formation of an irregular path for the balls. Moreover, when the adjustment is made from one side only, as in former constructions, the fork is slightly sprung and the friction is increased, and if the wheel is very closely built the fork is liable to strike the hub after repeated adjustments. Another objection to this construction is that the stationary collar frequently receives all or nearly all of the pressure exerted by the clamp of the bearing box or case, so that the adjustable collar is not securely held in position.

By my improved construction the springing of the fork is obviated, as both collars are compelled to move together, and neither collar can move out of position unless the other collar is loose enough to move also. A further advantage of the construction is that the collars can be adjusted at any desired distance from the center of the bearing box or case E as may be necessary by simply screwing one collar farther into the case than the other before interlocking them. This enables the machine to be set up without deflecting the fork in case the latter happens to be a trifle too wide or too narrow, which is a frequent cause of extra friction in bearings as heretofore usually constructed. Each fork-arm F is constructed of tubing and tapered toward its lower end, and is secured to the lug E' by a horizontal screw-bolt, j, passing through openings formed in the fork and lug.

K is a stiffening-piece arranged in the lower end of each fork-arm, and whereby the latter is re-enforced. This stiffening-piece consists

of a short piece of tubing, as represented in Figs. 2 and 7, or a strip of sheet metal, as represented in Fig. 9. After the fork has been tapered the stiffening-piece is inserted into the same, and the lower portion of the fork is then partially flattened to give it the desired form by placing it in a suitable die and swaging or compressing the fork. The outer face 75 of the lug E' is provided with a convex or conical projection, l, and the inner face of the head of the bolt j is provided with a concave or conical seat, l', as shown in Fig. 2, the lower end of the fork being bent or curved to 80 fit between the conical surfaces of the lug and bolt-head. By constructing the fork in this manner the stiffening-piece K is also bent in the act of shaping the fork, and is thereby firmly secured in place. The stiffening-piece 85 K forms an additional thickness of metal, which prevents the bolt j from enlarging the hole in the end of the tubular fork.

The conical projection l of the lug receives a large part of the weight applied to the forks, 90 and thus relieves the bolt j, and it also increases the thickness of the lug E' and forms a long and secure seat for the threaded end of said bolt, thus producing a reliable connection. When a very light build is desired, 95 and very thin tubes are used for the fork-arms, or if the adjacent surfaces of the lug E' and head of the bolt j be made flat, the stiffening-piece K is preferably secured in the end of the tubular fork by riveting, soldering, or brazing; but in the construction illustrated in the drawings no additional fastening is required. The lower end of the fork is recessed in the usual manner, as shown in Fig. 1, to fit around the upper part of the case 100 E and prevent the same from turning on the bolt j as a pivot.

The fork of the rear wheel of the velocipede is constructed substantially like that of the front wheel, the stiffening-piece consisting of a strip of sheet metal, M, instead of a tube.

N is the hub of the rear wheel; N', the supporting-bolt passing through the same; n, the cones arranged on the inner sides of the fork-arms, and each having a screw-threaded opening, through which the threaded ends of the bolt N' pass, and n' is the screw-nut applied to the end of the bolt N'. The outer faces of the cones n are provided with conical seats 115 or depressions, o, against which the inner sides of the fork ends bear, and the inner face of the nut n' and the head n² of the bolt N' are provided with conical or convex projections which bear against the outer sides of the fork-arms, the lower ends of the fork-arms being bent to fit between these conical faces, as in the first-described construction.

This construction renders the forks light, durable, and comparatively cheap.

A single strip of sheet metal is sufficient for re-enforcing the forks of the rear wheel, and is less expensive than the tubular piece shown in the first construction.

P represents the spokes, which are arranged tangentially to the hub-flange B, each pair of spokes passing outwardly in opposite directions substantially at right angles to a radial line passing between their inner ends. It is desirable that the spokes of a bicycle-wheel be arranged as closely as possible to the fork to insure the necessary rigidity of the wheel with the least possible distance between the cranks. To enable this close build, the hub-flange B is provided with two annular rims, p p', arranged in different vertical planes and made of different diameters, the rim p having the largest diameter and forming the margin of the hub-flange and being arranged in rear of the face of the rim p', which is of less diameter, as represented in Figs. 1, 2, 5, and 9. Both of the rims p p' are provided with an annular series of perforations for receiving the inner ends of a row of spokes. The spokes attached to the internal rim, p', pass forwardly, while those of the external rim, p, pass backwardly and intersect the spokes of the internal rim, as shown in Fig. 1. By this construction of the hub-flange both sets of spokes are located outside of the hub-flange in close proximity to the forks without any intervening parts between the forks and spokes. Each row of spokes is given a smooth flat base, upon which the spokes rest and against which they draw without the danger of being abraded or otherwise injured by rubbing against the other row of spokes, as is the case when both rows of spokes are secured to the outer side of a single flange. This construction also permits a broken spoke belonging to the inner row of spokes to be replaced without loosening any other spoke. The outer rim, p, projects beyond the inner rim, p', a distance about equal to the width of the spokes, so that the latter lie as closely together as possible. This construction forms a rigid wheel which resists side strains and buckling more effectually than a wheel having a row of spokes arranged on each side of a single flange, and as there is no part of the flange between the spokes and the fork the construction permits a very narrow build.

The spokes are preferably tied or soldered where they cross each other in the usual manner.

Hubs having double rims p p' are equally desirable for wheels in which the spokes are set at less than a full tangent, so long as the spokes are desired to cross at or near the hub.

I am aware that in my patent, No. 325,420, I showed and described a construction of the upper part of a fork and steering-head, wherein a tubular fork is strengthened in certain portions by the insertion of a lining or stiffening-plate held in place by a screw, and that in my patent, No. 332,092, I showed and described a method of attachment of the neck and the tubular backbone with a tubular lining, all held together by bolts; and I do not claim either of these things, nor do I claim

the strengthening of the tube by a lining or re-enforce.

Prior to my present improvements it had been usual to construct the lower ends of front forks (such as are shown at F in Fig. 5) of drop-forgings formed into shape for attachment to the bearing-case, the securing-bolt (such as j) passing through the forging and not through the tube, and the fork ending above the bolt some distance, being there brazed to a stub of the forging. The same construction has been employed in rear fork ends (such as are shown in Fig. 9) where the rear forks were tubular; but this method is objectionable, because the fork ends made by it are heavy and expensive and the forks are weakened by the brazing, and for rear or smaller forks I believe it has had to be abandoned in favor of solid or semi-tubular constructions, but at a disadvantage to the rest of the fork. Now, by my improved construction I taper, flatten, curve, and shape the fork ends as required for attachment to the bearing-boxes or axle wholly by and in the fork-tube itself, inserting at the same time, without brazing or forging and before the formation is completed, a thin leaf, as shown at M in Fig. 9, or a core, as shown at K in Fig. 2, for a strengthening-piece, and a thickener or re-enforce to keep the end of the tube from crushing in the operation of forming and to gain the desired width and strength of bearing on the bolt j or N', for which the two thin thicknesses of the tube would otherwise be too little. The core is secured in place by the bolt j or N', and the strain of the bolt is thereby distributed along the walls of the tube ends. By forming the fork ends in this way I avoid both brazing and forging, both weight and weakness.

I claim as my invention—

1. In a journal-bearing, the combination, with a bearing box or case provided in its bore with right and left hand screw-threads, of two adjustable grooved collars arranged within said bearing-box and provided on their outer surfaces with right and left hand screw-threads, respectively, and having their inner adjacent portions beveled and made of smaller diameter than the main screw-threaded portions of the collars, and beveled segmental ribs or projections arranged on the inner faces of said reduced portion of the collars, substantially as set forth.

2. The combination, with the axle having a contracted cylindrical extension, a', and the hub-flange B, having a tubular extension, B', of a crank, C, arranged upon said tubular extension, a screw-nut, c, applied to the end of the axle-extension a', a grooved collar or sleeve, D, arranged between the hub-flange and the crank, grooved adjustable collars G G', and a bearing box or case, E, surrounding the collars G G', substantially as set forth.

3. The described improvement in the construction of a tubular fork end for attachment

to a bearing in a velocipede, consisting in the extension of the tube end, the tapering, flattening, and forming the same with the insertion of a core, and the perforation of the two parts thus conformed together for attachment directly to the bearings, substantially as set forth.

5 4. The combination of a tubular fork-arm and a tubular fork end wrought thereon, and a strengthening-core inserted and conformed therewith, and a bolt passing through the fork end and its core and with its nut and shoulder securing the same directly to the bearing parts, substantially as set forth.

5 5. The combination, with a tubular fork-arm having a bent or concavo-convex lower end, or a stiffening or re-enforcing piece arranged in the lower end of the fork-arm, and supports having similarly-shaped faces bearing against opposite sides of the fork-arm, substantially as set forth.

6. The combination, with a tubular fork-arm having a bent or concavo-convex lower end and a stiffening or re-enforcing piece arranged therein, of the bearing box or case having a lug provided with a conical projection, and a fastening-bolt passing through the fork end and said lug, substantially as set forth.

5 7. The combination, with a tubular fork-arm having a bent or concavo-convex lower end and a stiffening-piece inserted in said lower end, of the bearing box or case having a lug provided with a conical projection bearing against one side of the fork end, and a

fastening-bolt, whereby the fork end is secured to said lug, and having in its head a conical seat, against which the opposite side of the fork end rests, substantially as set forth.

8. The combination, with two independent rows or sets of spokes, of a hub flange or disk provided with two annular rims arranged in different vertical planes, each of said rims supporting the inner ends of one set of spokes, substantially as set forth.

9. The combination, with a hub flange or disk provided with an internal annular rim and an external annular rim arranged in different vertical planes, of a set of spokes attached to said internal rim and a set of spokes attached to said external rim, the spokes attached to one of said rims passing outwardly from the hub in a direction substantially opposite to that of the spokes attached to the other rim, substantially as set forth.

10. The combination, with the axle, of two hub-flanges, each provided with two marginal rims arranged in different vertical planes, and each provided with two sets of spokes arranged against the outer sides of said rims, whereby the spokes of one set draw over the spokes of the other set, and both sets draw over the outer sides of said rims, substantially as set forth.

Witness my hand this 16th day of January, 65
1888.

EMMIT G. LATTA.
